UNITED STATES PATENT OFFICE.

TORAKI KITAOKA, OF LOS ANGELES, CALIFORNIA.

NOISELESS RAILWAY-CROSSING.

1,275,267.

Specification of Letters Patent. Patented Aug. 13, 1918.

Application filed February 25, 1918. Serial No. 218,986.

To all whom it may concern:

Be it known that I, TORAKI KITAOKA, a subject of the Emperor of Japan, residing at Los Angeles, in the county of Los Angeles 5 and State of California, have invented a new and useful Noiseless Railway-Crossing, of which the following is a specification.

This invention has relation to improvements in devices for forming a continuous 10 rail or rails at a railway crossing, and its objects are to provide means for avoiding the pounding of the wheels of a railway car in passing the crossing, and to provide simple, inexpensive, and effective parts and 15 combinations of elements for accomplishing this purpose.

Another object is to provide a device of this character which is reliable in use and entirely automatic in operation.

20 This description is the disclosure of one form of the invention, while the claim defines the actual scope thereof.

In the drawings, Figure 1 is a vertical mid-section of a railway crossing to which 25 my invention has been applied. Fig. 2 is a detail perspective view of an operating lever employed in my device. Fig. 3 is a fragmental plan view showing the parts in reverse position from that shown in Fig. 1.

30 Fig. 4 is a fragmental and sectional elevation with the parts in position as shown in Fig. 3. Fig. 5 is a plan view of the crossing. Referring to the drawings, the main rails 6, 7, of intersecting tracks, are of the grooved 35 type having inner upturned flanges 8, and provided with spaces 9, 10, allowing the passage of the wheel flanges of a passing car, and adapted to be filled by suitable blocks 11, 12, respectively, which are shifted

40 to operative position to form a continuous and practically unbroken rail surface for a car going in either direction, the blocks being automatically shifted in sets to operative position, and one set being shifted to inoperative 45 position as the other is shifted to operative position.

The block actuating levers 13, connected to the main rails by pivotal means 14, are mounted in slotted portions of the rails, 50 with their upper surfaces 15, and the blocks 11, 12, normally flush with the upper surface of the adjoining rails. When in operative position, blocks 11 or 12, rest upon supporting ends 16, of the movable bars 17, 55 which are maintained in operative position by springs 18, interposed between the bars

and retaining members 19, on rods 20. The actuating levers 13 are provided with inclined faces 21 adapted to engage with the flanges of the approaching car wheels and 60 be operated thereby. Levers 13 are supported by link members 22, 23, and the downward movement of levers 13 will cause an angular movement of said link members and actuate the bar 24 which is connected to 65 link member 23. Bars 24 are provided with upwardly extending lugs 25, which engage with the movable bars 17, and, as levers 13 are depressed, shift the ends 16 to release position, and allow the blocks 11, 12, to 70 move downwardly into the position as shown in Fig. 3.

Means for simultaneous movement of the supporting and filling blocks 11, 12, to automatically fill certain of the spaces and thus 75 form continuous rails for a track, consist of compound bell-crank levers 26, having crank-arms 27, 28, and 29, arranged to swing in different planes, and interconnected by the links 30, for operating in unison to actuate 80 the bars 24.

Assuming the crossing to be in the position as shown in Fig. 5, with the gap-closing elements 11 in working position and trip levers 31 in raised position, a car approaching the crossing on track-rails 6, will depress the levers 31, thus moving the links 22, 23, to actuate the corresponding locking bar and withdraw the supporting ends 16 from beneath the blocks 11 which will be depressed 90 to allow the passage of the wheel flanges. Simultaneously the levers 21 will be raised, and the corresponding filler blocks 12 will be shifted to operative position, being lifted by the lugs 32 on the actuating levers. 95 When the blocks 12 are in operative position, the bars 17 and their supporting ends 16 are actuated by the springs 18, to operative position, being interposed between the blocks 12 and pillow members 33. The outer ends of link members 24 move between roller guides 34, and the supporting blocks 11 and 12, and levers 13 and 31, are retained in position by rail flanges 8. It will be noted that blocks 11 and 12, are pivotally connected to their respective actuating levers 13 and 31, so that the blocks are tilted upon depressing the actuating levers.

The arrangement of the connecting links 24 and 30, with compound levers 26, is such 110 that when the blocks are raised to bridge the gaps in one track, they are lowered in

the grooves of the other track so that the wheels of a car will pass the intersecting track without jolt or noise.

While the described combination of railway crossing elements is well adapted to serve the purposes for which it is intended, it is to be understood that no limitation is made to the precise details set forth, but changes may be made in accordance with 10 the appended claim.

What is claimed is:

The combination with a railway crossing having gaps at the points of intersection, vertically movable blocks adapted to bridge 15 the gaps, spring-actuated bars normally supporting the filler blocks in operative position, actuating levers adapted to be de-

pressed by the flanges of approaching car wheels, angularly disposed links supporting the actuating levers, horizontally disposed links connecting the angular links with the spring-actuated bars, compound bell-crank levers to actuate the horizontally disposed links, and interconnecting links for the compound bell-crank levers whereby simultaneous movement of the spring actuated bars is effected.

In testimony whereof I hereunto affix my signature this 19th day of February, in the year 1918.

TORAKI KITAOKA.

In presence of—

S. HATAYE,

J. W. MOSHER.
